TITLE COVERED, FIREPROOFED
STRUCTURAL ELEMENT

John P. Marcy, Alhambra, Calif.

Application January 2, 1948, Serial No. 318

4 Claims. (Cl. 72—73)

1

This invention relates to the field of building and construction and more specifically to fireproofing of steel structures and buildings, particularly the load-bearing structural steel thereof.

The primary object of this invention is the provision of fireproofing structure taking the form of pre-cast blocks disposed in end-to-end relationship along the particular member to be fireproofed and having interlocking structure for holding the blocks in place that is quickly and easily positioned for use and is efficient in its function of holding the blocks together.

The most important object of this invention is to provide fireproofing blocks having interconnecting means either in the inherent contour of the blocks themselves or through use of a specially formed key that will prevent separation of the blocks and the sections thereof once the same are positioned on the member to be protected.

Many additional objects will be made clear during the course of the following specification, reference being had to the accompanying drawing, wherein:

Fig. 1 is a side elevational view of a vertical structural steel column showing the same fireproofed using one form of my present invention, parts being broken away for clearness.

Fig. 2 is a cross sectional view taken on line II—II of Fig. 1.

Fig. 3 is a fragmentary cross sectional view taken on line III—III of Fig. 1.

Fig. 4 is a cross sectional view taken on irregular line IV—IV of Fig. 3.

Fig. 5 is a cross sectional view similar to that shown in Fig. 2 showing a modified form of key.

Fig. 6 is a cross sectional view similar to that shown in Fig. 5 showing another modified form of key.

Primarily the fireproofing structure about to be described is for use on load-bearing structural steel such as used in oil refinery and chemical plants, although buildings generally may well have the framework thereof so fireproofed. In oil refineries particularly, steel framework subjected to fires creates an extremely hazardous condition unless adequately protected against possible fire.

Many buildings, although capable of opposing the access of fire from without, but having combustible contents, are far from deserving the name of fireproof, though they may resist a certain amount of scorching. Thus it has been the practice to separately fireproof load-bearing structural steel but the methods used have been expensive. This expense has been recently enhanced by high cost of lumber and construction labor. Such fireproofing by poured concrete or

like methods has therefore become almost prohibitive.

The fireproofing means about to be described contemplates the use of pre-cast blocks made from red clay such as is commonly used in hard red brick, concrete or other structurally suitable material capable of being formed into blocks and having fire and weather resistant characteristics.

The embodiment of my invention shown in the accompanying drawing includes the use of separate fastening means for holding the block sections and the blocks themselves together.

The form of fireproofing illustrated in the drawing is shown on a vertical H-shaped structural steel frame member 10 that is conventionally connected to a base plate 12. A sectional base block 14 has a recess 15 formed therein to clear the plate 12 and its fastening means. This base block 14, as well as the sectional blocks

20 about to be described, is made from any material capable of casting or molding into the shape desired and having fire and weather resistant characteristics as well as being sufficiently durable to be structurally suitable. Such material 25 may be red clay such as is commonly used in hard red brick, concrete or the like.

The blocks which circumscribe the member 10 upwardly from base block 14 are broadly designated by the numeral 16 and are positioned in 30 end-to-end relative abutting relationship to completely cover the member 10. These blocks 16 are sectional, there being a pair of sections 18 and 20 in the embodiment shown of identical character. As shown most clearly in Fig. 2, each 35 of the sections 18 and 20 is U-shaped in cross section and formed to embrace substantially one-half of the member 10 when positioned thereon.

One leg of the section 18 has a longitudinal, internal groove 22 formed therein to receive a 40 longitudinal rib 24 of the opposed leg of section 20. The opposite leg of section 18 has an external, longitudinal groove 26 to receive an external rib 28 on the opposed leg of section 20. It is clear that a lap joint is thus formed between the sections 18 and 20 at each of their opposed legs.

As shown in Fig. 1, lap joints 30 are also formed between the blocks 16 by providing each section 18 and 20 with an external groove along one edge of the bight thereof and an internal groove along the opposite edge of its bight.

The internal faces of the legs of each section 18 and 20 have longitudinal grooves 32 formed therein that extend from one end of the sections 50 to a point intermediate the ends thereof. These grooves 32 receive the legs of a U-shaped key 34 that is also provided with a centrally disposed

projection 36 extending oppositely from the said legs of key 34.

The base block 14 is also provided with vertical grooves such as at 32 for receiving keys 34 and is formed to cooperate with sections 18 and 20 to present a lap joint 38 with the first block 16.

After base block 14 is positioned over plate 12 and around a portion of member 10, a pair of keys 34 are inserted within the grooves of block 14. These keys 34 have a length sufficient to extend a distance above block 14 and are disposed in opposed relation on each side of member 10 with the projections 36 thereof wedged tightly against the center cross plate of member 10.

The first block 16 is then slipped into place with all lap joints interlocking and with that portion of the keys 34 above block 14 received by the respective grooves 32.

The next step is to insert another set of keys 34 into grooves 32 from the uppermost edge of the first block 16. These keys 34 will rest upon the innermost ends of their respective grooves and extend outwardly therefrom for receiving the next block 16.

It is to be noted that the keys 34, which are formed from the same material as blocks 14 and 16 serve not only to hold sections 18 and 20 together but prevent any possible displacement thereof in any direction. The manner in which keys 34 overlap the lap joints 38 and bring together the sections 18 and 20 at their point of interlocking adds to the durability and strength of the fireproofing structure.

A cap 40 takes much the same form of the keys 34 as shown in Figs. 3 and 4 and is sectional to close the fireproofing wall either at a desired point along the member 10 or at its end. This cap 40 is also formed to cooperate with the block 16 next adjacent thereto to form a lap joint on all sides as at 42 and completely fills in the entire space surrounding the member 10.

In Fig. 5 a modified form of key 50 is shown to hold together the sections 52 and 54 of a block 56 of identical character as block 16 just above described. This key 50 is preferably formed from asbestos cement and is substantially U-shaped in cross section. The legs of this key 50 have inturned ears 58 formed thereon which are received by grooves 60 within the inner faces of the legs of U-shaped sections 52 and 54. The two legs of key 50 rest flatly along the two inner faces of the respective side walls of the H-shaped member 62 while the bight thereof is wedged tightly against the center cross bar of member 62. The length of grooves 60 and of keys 50 and the manner of assembling is the same as above described with respect to the modification of Figs. 1 to 3 inclusive.

In Fig. 6 a metallic key 70 of U-shaped cross section is shown placed in a block 72 in the identical manner as key 50 of Fig. 5. In this case, however, the legs of key 70 extend directly into grooves 74 formed in block 72 to hold the sections thereof in place.

It is to be noted that the form shown in Figs. 1 to 6 inclusive is illustrated on a vertical column, but the blocks and keys thereof may well be used on horizontal beams.

Having thus described the invention what is claimed as new and desired to be secured by Letters Patent is:

1. Fireproofing structure for a pre-formed, metallic, elongated H-beam, said structure comprising a plurality of pre-formed, fire-resistant

blocks disposed in end-to-end and abutting relationship throughout the length of and in complete circumscribing arrangement to said beam, the abutting edges of the blocks being in shiplapped relationship, each block including a pair of opposed, U-shaped sections with the remote edges of opposed leg portions thereof in abutting relationship, the abutting edges of the leg portions of the sections being in shiplapped relationship; and means holding the sections against lateral displacement relative to the beam, said means comprising a pair of opposed, pre-formed keys interposed between the beam and the blocks and each directly engaging the beam and both sections of the blocks and holding the blocks against movement in one direction relative to the beam, each section having a pair of grooves therein receiving portions of the keys, whereby the keys hold the sections against separation.

2. Fireproofing structure as set forth in claim 1, wherein one of said pair of grooves of each section is on the inner surface of one leg portion of the section, the other of said grooves of each section is on the inner surface of the other leg portion of the section, and each key is provided with a U-shaped portion presenting a pair of spaced legs on the key, the legs of each key being respectively disposed within and in engagement with a groove of each of the sections.

3. Fireproofing structure as set forth in claim 1, wherein one of said pair of grooves of each section is on the inner surface of one leg portion of the section, the other of said grooves of each section is on the inner surface of the other leg portion of the section, and each key is provided with a U-shaped portion presenting a pair of spaced legs on the key, the legs of each key being respectively disposed within and in engagement with a groove of each of the sections, said U-shaped portion of each of the keys being wedged between opposed parts of said beam.

4. Fireproofing structure as set forth in claim 1, wherein one of said pair of grooves of each section is on the inner surface of one leg portion of the section, the other of said grooves of each section is on the inner surface of the other leg portion of the section, each key is provided with a U-shaped portion presenting a pair of spaced legs on the key, the legs of each key being respectively disposed within and in engagement with a groove of each of the sections, and each key is provided with a projection extending from the bight of the U-shaped portion of the key in a direction oppositely to said legs thereof, said projection of each key bearing against the beam, said bight of the U-shaped portion of each key bearing against the blocks.

JOHN P. MARCY.
